CLAIM

The ornamental design for a vehicle wheel, as shown and described.

DESCRIPTION

FIG. 1 is a front perspective view of a vehicle wheel embodying my new design in accordance with a first embodiment;

FIG. 2 is a front view of that seen in FIG. 1;

FIG. 3 is an additional front perspective view of that seen in FIG. 1;

FIG. 4 is a front perspective view of a vehicle wheel embodying my new design in accordance with a second embodiment;

FIG. 5 is a front view of that seen in FIG. 4; and,

FIG. 6 is an additional front perspective view of that seen in FIG. 4.

The broken lines in the drawings illustrate portions of the vehicle wheel that form no part of the claimed design.

1 Claim, 6 Drawing Sheets
